UNITED STATES PATENT OFFICE.

SAMUEL PRICE STEVENSON, OF CHESTER, PENNSYLVANIA.

SPRING FOR DOOR-FASTENERS.

965,418.

Specification of Letters Patent. Patented July 26, 1910.

Application filed October 31, 1906. Serial No. 341,371.

To all whom it may concern:

Be it known that I, SAMUEL PRICE STEVENSON, of Chester, in the county of Delaware and State of Pennsylvania, have 5 invented certain new and useful Improvements in Springs for Door-Fasteners, whereof the following is a specification, reference being had to the accompanying drawings.

My invention relates to latch fasteners of 10 the type heretofore invented and patented by me in United States Letters Patent No. 633,536, dated September 19th, 1899, and especially adapted for use in fastening the doors of refrigerator compartments where- 15 in a very firm and close fit and fastening of the door is required. In the construction of these fasteners it is important to have a strong and durable spring not affected by rusting due to moisture, or by wear, and 20 capable of maintaining with the proper degree of firmness, the engagement of the latch with its keeper. For this purpose as shown in said patent, a strong flat rectangular spring has hitherto been employed by me, 25 arranged so as to constitute a lever of the first class with a fulcrum in the middle, a bearing point at the lower end, and a pressure point at the upper end. But I have experienced difficulty owing to the tendency 30 of such a spring, when rectangular in shape as shown in said patent, to eventually break or become permanently set at or near the center where it passes over the fulcrum point. This is because in a flat spring of 35 uniform width the greatest strain is experienced at that point, so that the bending action takes place chiefly there, and my present invention relates to means for so shaping a spring adapted for this purpose, 40 as to distribute the strain, and therefore the bending action, evenly along the whole length of the spring, thus preventing it from being bent. I thus have secured a 45 spring having a much greater life than those heretofore used without increasing the length or thickness of the spring, and therefore without increasing the size of the casting provided for my device. This is accom- 50 plished by tapering the edges of the spring toward its ends, with provision upon the lower end of an offset whereby the tapering is prevented from interfering with the proper support of the bearing end of the spring.

55 In order to secure the maximum effective

length of spring in the minimum size of cas- 60 ing, I find it desirable to taper one end of the spring upon one side, and the other end upon the other side, so that the extreme length of the spring is a diagonal one.

In the drawings, Figure I, is a front elevation of my improved door fastener contain- 65 ing a spring embodying my present invention. Fig. II, is a section along the line II, II, in Fig. I. Fig. III, is a detail view of my improved spring.

In explanation of the construction shown in the drawings, the door 1, abutting against the door casing 2, is provided with a fastener contained within a casing 3, secured to the 70 door by means of screws 4. Extending through the enlarged portion 5, of this cas- ing is the latch 6, provided with an exterior handle 7, operated as a lever from the out- side of the door, to move the latch 6, to 75 which it is attached. The inside of the cas- ing is provided with a recess 8, which re- ceives and holds firmly in place the lower or bearing end of the flat spring 9, the cen- 80 tral portion of which rests against a ledge 10, forming a fulcrum for the spring action, while the upper end of the spring resists the under side of the enlarged portion 11, of the latch operating handle. The ledge 10, is formed upon a plate 12, secured within the 85 casing.

The peculiar shape of the spring 9, upon which my present invention depends is most clearly exhibited in Fig. III, where it will be noted that the central portion of the 90 spring, where it bears against its fulcrum, is of the full width of the ordinary flat spring hitherto employed by me. Toward the lower end 13, the spring is diminished in width or tapered, the diminution being 95 effected altogether upon one side with pro- vision of an offset 14, at the extreme end, the purpose of which will be hereafter ex- plained. The upper end of the spring is simi- 100 larly tapered, the diminution in width being effected entirely upon the opposite side from that which is narrowed to form the taper of the lower end. The offset 14, enables the base of the spring to be main- tained of full width, so as to afford a firm 105 engagement for its lower end with the recess 8, provided for it in the casing. This is important because the proper seating of the spring without the creation of sidewise or torsional strains can only be thus secured. 110

The taper of the spring toward its ends has the result of spreading the bending action evenly over the length of the spring thus distributing the strains which otherwise would occur chiefly along the line of the fulcrum 10. This result is accomplished without weakening the power of the spring, without enlarging the spring, and therefore within the limits of the usual sized casing, 10 and without any other objectionable modification of the device. In other words, by cutting away certain specific portions of the flat spring heretofore employed by me, I have secured a much better and more lasting device, lengthening the life of the spring and avoiding the danger of permanent set.

Having thus described my invention, I claim:—

1. In a fastening device, a flat spring fulcrummed at its center and tapered toward either end, one end of the spring being fixedly seated and the other forming a point

of resistance for the latch operating members.

2. In a spring controlled latch fastener, 25 the combination of a casing provided with a seat; a fulcrum bridge; a flat spring resting at its lower end in the seat, abutting midway against the fulcrum ledge, and with its upper and free end resisting the latch 30 operating mechanism, said spring being tapered toward both ends, and with an offset at its lower end whereby the portion which engages the seat is maintained at full width.

In testimony whereof, I have hereunto signed my name, at Philadelphia, in the State of Pennsylvania, this twenty-ninth day of October, 1906.

SAMUEL PRICE STEVENSON.
